UNITED STATES PATENT OFFICE.

FLOYD J. NIFFENEGGER, OF NEAR KALONA, IOWA.

STOCK WATER HEATER.

Application filed June 15, 1923. Serial No. 645,629.

To all whom it may concern:

Be it known that I, FLOYD J. NIFFENEGGER, a citizen of the United States, and resident of near Kalona, in the county of Johnson and State of Iowa, have invented certain new and useful Improvements in Stock Water Heaters, of which the following is a specification.

An important purpose of the present invention is to provide a drinking trough combined with a water heater embodying a combustion chamber and wall portions intervening between the said chamber and the bottom of the trough to shield the latter from direct contact with the flames whereby the life of the trough is considerably prolonged.

A further purpose of the invention is to provide float controlled means regulating the supply of water to the trough and including a feed pipe extending through the body of the heater so as to be exposed to the heated gases generated therein.

Other purposes and advantages of the invention, not specifically stated in the foregoing, will become apparent from the following detailed description and accompanying drawings.

In which—

Fig. 1 is a view in side elevation of a water tank and heater constructed in accordance with my invention.

Fig. 2 is a vertical longitudinal sectional view through the construction shown in Fig. 1, and

Fig. 3 is a transverse sectional view taken on the line 3—3 of Fig. 2.

Referring more particularly to the drawings, 5 represents a rectangular furnace or heater casing closed at the top, bottom, sides and ends and provided interiorly with upper and lower plates 6 and 7 extending rearwardly from the front casing wall 8 to a point spaced from the rear wall 9. The upper plate 6 constitutes a baffle extending in spaced parallelism with the top casing wall 10 and, at a point directly above the forward end of the plate, the said top wall 10 is provided with a smoke outlet collar 11 receiving thereon the lower end of a smoke pipe 12. The lower plate 7 which extends in spaced parallelism with the bottom casing wall 13 carries a suitable grate 14 and terminates in a vertically extending wall 15 which serves to prevent the ashes from being pushed off of the rear end of the grate

onto the bottom of the casing and also acts as a deflector for directing the products of combustion toward the top wall 10, it being understood that the plates 6 and 7 extend the full width of the casing and cooperate with the side and front walls of the latter to form a combustion chamber 16, into which the fuel is deposited through a feed opening 17 formed in the front casing wall 8. The said front wall 8 is also provided with a draft opening 18 positioned between the plate 7 and the bottom of the casing and with a clean out opening 19 positioned between the baffle 6 and the top of the casing, the latter opening being utilized for removing the soot accumulating on the upper surface of the said baffle.

In accordance with my invention, the top wall of the casing 5 is utilized to support thereon a rectangular drinking trough 20 which is open at the top and is provided with an arrangement of longitudinal and transverse wires 21, affording individual drinking openings 22, each of which is of sufficient size to permit the head of a single animal to extend therethrough.

Water is supplied to the trough 20 through a feed pipe 23 extending upwardly through the bottom and top walls of the casing 5 and through the bottom wall of the trough 20, the upper end of said pipe being equipped with any suitable type of valve controlled by a float 24, in such manner as to keep the water in the tank 20 at a substantially constant level.

In the use of the device, the fuel is introduced into the combustion chamber 16 through the feed opening 17 and the products of combustion issuing from the said chamber 16 are directed by the vertical wall 15 into contact with the top casing wall 10 to pass forwardly between the lower surface of said wall 10 and the upper surface of the baffle 6 to the outlet 11 and smoke pipe 12. In this connection it is pointed out that the baffle 6 and top wall 10 of the casing serves not only to shield the bottom of the trough from the flames generated in the combustion chamber 16, but also act to absorb a considerable amount of the heat generated so that the temperature of the water in the trough 20 will not be raised to an excessive degree, but will be maintained at a temperature somewhat above the freezing point.

Preferably the trough 20 is made to extend the full width of the casing, but is

somewhat shorter than the said casing so as to extend from the rear wall 9 to a point in spaced relation to the front wall 8, thereby leaving the forward portion of the top wall 5 exposed to provide for the connection of the smoke pipe 12 to the outlet collar 11. With this arrangement, the casing 5, instead of being mounted on the surface of the ground as shown in the present illustration 10 may be placed in a shallow pit or ditch so that the top wall of the casing will be level with the ground surface and, in such event, the clearance reserved between the forward end of the trough 20 and the smoke pipe 12 15 will enable a fence to be built around the latter to prevent the animals from displacing the said pipe when crowding around the water tank.

It has been found in practice that the use 20 of a single baffle 6, positioned as shown between the grate 14 and the top wall of the casing 5 provides for an improved and desired circulation of the products of combustion issuing from the chamber 16.

Having thus fully disclosed what I now consider to be the preferred embodiment of my invention, I reserve the right to resort to such changes in the detail construction and relative arrangement of parts as may later 25 prove desirable, providing, of course, that the contemplated changes come within the scope of the appended claims and do not constitute a departure from the spirit of the invention defined thereby.

What I claim is:

1. A device of the character described comprising a drinking trough open at the top, a heater including a casing positioned

with its top wall underlying and supporting the bottom wall of the trough, upper and lower plates extending rearwardly from the front wall of the casing and defining an intervening combustion chamber, said upper plate being spaced from the top wall of the casing to provide a return flue leading forwardly to an outlet formed in the top wall of the casing at a point adjacent the front wall thereof, said lower plate being equipped to form a grate and being spaced from the bottom wall of the casing to provide an intervening draft passage and a smoke pipe connected with the aforementioned outlet.

2. In a device of the character described, the combination of a drinking trough open at the top, a heater comprising a casing including a top wall underlying and supporting the bottom wall of the drinking trough, upper and lower plates extending rearwardly from the front wall of the casing and defining an intervening combustion chamber, said upper plate being spaced from the top and rear walls of the casing to provide a return flue extending forwardly to an outlet formed in the top wall of the casing at the front end thereof, said lower plate being equipped to form a grate and being spaced from the bottom wall of the casing to provide an intervening draft passage and a vertical wall formed at the rear end of said lower plate to provide a guard preventing 60 ashes passing over the rear end of the grate and on to the bottom wall of the casing.

In testimony whereof I hereunto affix my signature.

FLOYD J. NIFFENEGGER.
